UNITED STATES PATENT OFFICE.

RALPH BAGGALY, OF PITTSBURG, PENNSYLVANIA, CHARLES M. ALLEN, OF LO LO, MONTANA, AND EDWARD W. LINDQUIST, OF CHICAGO, ILLINOIS, ASSIGNORS, BY DIRECT AND MESNE ASSIGNMENTS, TO PITTSBURGH AND MONTANA COPPER COMPANY, OF PITTSBURG, PENNSYLVANIA, A CORPORATION OF WEST VIRGINIA.

MEANS FOR INCREASING THE AIR-BLAST OF CONVERTERS AND FURNACES.

No. 871,079.

Specification of Letters Patent.

Patented Nov. 12, 1907.

Application filed May 13, 1905. Serial No. 260,212.

To all whom it may concern:

Be it known that we, RALPH BAGGALY, of Pittsburgh, Allegheny county, Pennsylvania, CHARLES M. ALLEN, of Lo Lo, Missoula county, Montana, and EDWARD W. LINDQUIST, of Chicago, Cook county, Illinois, have invented a new and useful Means for Increasing the Air-Blast of Converters and Furnaces, of which the following is a full, clear, and exact description, reference being had to the accompanying drawings, forming 10 part of this specification, in which—

Figure 1 represents a front elevation of a portion of a converter equipped with one form of apparatus embodying our invention. Fig. 2 represents an end elevation of the mechanism illustrated in Fig. 1. Fig. 3 represents a cross-section of a converter, showing one twyer, the wind-box, one form of punching-bar and the levers of the mechanism that actuate the punching-bar in different positions. Fig. 4 illustrates the details of the sleeve shown on the punching-bar in Fig. 3, whereby it may be secured at any desired point on the bar, through the medium of a set-screw and gib. Fig. 5 illustrates an alternative form of punching-bar, which can be adjusted accurately with hand-wheels and which is provided with a head, so 25 that a wrench or "dog" may be attached for its removal by hand, in the event of accident to the mechanism. Fig. 6 illustrates an end view of Fig. 5. Fig. 7 illustrates in cross-section, one twyer and the cutter-plug that is used in removing scale from the punching-bar, each time the latter is withdrawn from the orifice. Fig. 8 is a section on the line I—I of Fig. 7. Fig. 9 is a side view of the plug, showing the grooves for the passage of the air-blast into the converter. Fig. 10 illustrates end views of two plugs in position in the 30 converter wall; together with convenient, hinged screw-clamps for holding them firmly in place. Fig. 11 illustrates a side view; together with a converter in cross-section, of another apparatus that may be successfully used, in practicing our invention. Fig. 12 shows a plan view of Fig. 11. Fig. 13 shows an end view of Fig. 11, partly in section. Fig. 14 illustrates a modified form of Fig. 11 equipped with apparatus for the removal of scale from the punching-bars. Fig. 15 shows a section on the line II—II of Fig. 14.

45 The object of our invention may be briefly stated to be:

1st.—To augment the air-blast delivered into converters or furnaces.

2nd.—To eliminate the present laborious, expensive and unsatisfactory method of punching tuyers by hand, in either converters or in furnaces of any kind, and to do this work by machinery intermittently or continuously, as may be preferred. Hand-punching

is unsatisfactory, not only on account of the negligence of the workman, but because it is necessarily slow, 55 whereby the punching bar remains in the converter long enough to become heated up to approximately the temperature of the bath, whereupon the molten slag and matte quickly attach themselves to the highly heated punching bar and thus choke and eventually 60 entirely close the twyer. Neither molten slag or matte can possibly attach themselves to a cold punching bar, hence an important object of the present invention is not only to work the punching bars rapidly but to maintain them in a cool condition when not actually 65 performing a punching operation.

3rd.—To prevent the clogging of the tuyers with chilled slag or matte as at present prevails, with its consequent expense and through a failure to deliver 70 the blast continuously into the charge with its reduction of the producing capacity of the vessel.

4th.—To realize the economies and the certainties that result from doing such work thoroughly and at stated intervals by machinery, according to the requirements of the metallurgical work in hand; instead 75 of attempting to accomplish the desired result by manual labor, with its well-known uncertainties and its failures.

In present converter practice, the vessel is tipped from time to time as a means of discharging the slag, 80 and during the period occupied in this work, the blast must be shut off; hence no special attention need be given to the tuyers, inasmuch as these are elevated above the level of the molten bath while the converter is thus tipped. This occurs about once in every hour. 85 At the end of stated periods, say at least once in three or four hours, the entire charge is poured. It is also necessary once in every twenty-four hours to change or to renew the lining of the converter. During the intervals between charges, it is often necessary to repair 90 the lining. Such frequent stoppages require time and they give the workmen employed as twyer-punchers a chance to rest. Were it not for these, it would be physically impossible for one set of twyer-punchers by manual labor to keep the tuyers of the ordinary converter open and in a condition for the blast to enter the molten bath. Even under present conditions, the work is extremely laborious and exacting.

It is the intention, by means of our invention, to make it possible to practice the art disclosed in United States Patent No. 766,654, issued August 2nd, 1904 and especially that portion of the process that is described more in detail in Serial No. 243,677, filed February 1st, 1905. It will be apparent however that our invention may be used with great success and economy 105 in connection with other converters and furnaces.

In the large primary converter which is fully described and illustrated in the inventions above referred to, there is no pouring of slag, no repairing of the lining, no renewal of the lining, and in fact none of the delays, that are customary in ordinary practice. For this reason, it would be necessary with it for the workmen to be engaged continuously throughout an entire shift in punching the twyters, in order to keep these open, so that the converting blast could enter the molten bath effectively. The large converter referred to is provided with thirty-two twyters; hence more twyters would manifestly have to be kept in working order by the workmen than prevails in present practice.

In the special work described in the inventions above referred to, it is the intention to use this large converter exclusively in melting a primary bath of sulfid ores. That is to say, in melting a bath from ores that are rich in sulfur, iron and other oxidizable elements and compounds. Such a bath will necessarily be hotter, more fluid and more corrosive than ordinary converter mattes such as are usually treated in converters; hence, ordinarily speaking, there will not be as much trouble in keeping the twyters free and open and in continuous operation, with this large primary converter as would be the case when ordinary converter mattes were under treatment. Notwithstanding this fact however, it will be apparent that it would be extremely difficult, if not physically impossible, for one set of twyer-punchers to keep thirty-two twyters even in this large primary converter in operation by continuous manual labor throughout an entire shift. We have therefore invented means by which this work can be done by machinery.

In the process of treating ores, described in the inventions above referred to, we can operate converters continuously in doing the work, and in smelting the ores that are ordinarily smelted in blast furnaces. Until our discovery of a method of operating converters continuously without relining them, as described in the said inventions, it was not possible to do this class of work in a converter.

The twyters in ordinary blast furnaces vary from three and one-half to six inches in diameter, and the level of the melted material is always kept below their level. For this reason it is not difficult for the workmen to keep them open and in continuous operation, assuming that other conditions in the furnace are favorable. Because of this there will not be the same necessity for our invention in connection with furnaces that will exist in all converter work. Another point is the fact that furnace walls remain in a fixed, permanent position; hence the mechanical problem of attaching our twyer-punching mechanism is a simple one, when compared to that of a tipping converter. We have for this reason, not shown drawings of the apparatus attached to a fixed furnace. In converter work, the twyer-orifice is seldom if ever more than one and one-quarter inches and the punching-rod is seldom more than seven-eighths of an inch in diameter. The molten charge too, in contradistinction to that in the blast furnace, is practically always kept above the twyer level, and it must be above this level while converting is in progress. It will therefore be apparent that when a converter is utilized, as in our case, to do the work

of a smelting furnace in melting ores, some method of keeping the converting twyters in continuous free operation is of great importance. It is a well known fact that a few moments neglect of a converter twyer often puts it out of operation, permits it to become clogged with congealed slag or matte and renders it difficult to reopen, so that the converting blast may again pass through it and so that it can do effective work. It will be apparent that a few such clogged twyters in a converter will seriously retard the work and that they will proportionately reduce the productive capacity of the vessel. Where continuous operation is required, as in our case, unless provision be made for keeping the twyters always open by machinery; the inevitable result will be serious complications, which will in a short time bring the work to a full stop.

We have discovered that the best method of preventing clogged twyters, is to punch each separate one in the vessel, so often and so rapidly that there can be no chance for chilled accretions to clog and to obstruct them. This result can manifestly be attained better through the medium of suitable machinery, than it is possible to do by manual labor. In the drawings we illustrate two forms of apparatus with which our invention may be practiced. Other forms may be used for the purpose, without departing from its spirit.

We believe that our means of increasing the air-blast of converters and of furnaces by machinery is broadly new, and as such we intend to claim it.

Our means of punching twyters not only saves a great amount of labor, but by steady and continuous work, such as it is impossible to secure by manual labor, it becomes the means of affording an efficiency in the blast and of producing effective results in a given time that cannot be approached by any existing method. It should be noted in this connection, that the entering blast produces an oxidation of the sulfids of the base metals, and that the success of the process will depend solely upon the free entrance of the air through the twyters. Our invention offers a feasible and reliable method of accomplishing this result, especially on so large a scale.

Ideal practice would be to punch each twyer periodically by suitable mechanism as often as may be found necessary to keep it entirely free, open and clear from congealed obstructions. The frequency of such punching will necessarily be governed largely by the character of the material under treatment. Some materials such as high-grade matte, slag or blister copper will congeal more rapidly than molten sulfids. It is the intention that this punching shall be done periodically and continuously, say for instance, in a converter having sixteen twyters, two can be punched at one time and this could be followed by two others, so that in one complete revolution of the machine-shaft, the entire sixteen twyters would be thus punched in pairs. This would have the effect of keeping all of the twyters open and free so that the blast would be enabled to act continuously at its maximum efficiency. It would also have the effect of keeping the molten contents in a hot, fluid state so that there will not be the same tendency to clog and to close the twyters, that now exists where irregular and spasmodic hand-punching is resorted to. The producing capacity of the vessel may thus be enormously increased in a given time, over that of any

similar vessel in which the twyers are punched by hand.

In the first apparatus illustrated in the drawings, it is the intention that each separate twyer shall be punched once every sixty seconds and that the point or tip of the punching-bar shall obstruct or shut off the entering blast only for a period of five seconds at each entrance of the rod. Those skilled in the art will appreciate the fact that this is in marked contrast with 10 present practice.

Attention is called to the fact that the punching rod is purposely made so much less in diameter that a free passage for the entering blast is left around it in the twyer-orifice at all times, excepting during the five seconds that the rod is in actual contact with the slag or matte that forms the interior coating of the converter wall. It is also worth noting that the volume of blast that enters the converter cannot be measured, as is popularly supposed, by the diameter of the twyer-orifice. Its volume is governed solely by the size of the punching-rod, or in other words, by the size of the orifice that this punching-bar forces through the interior slag or matte lining on the interior wall.

An important element of success in practicing this art will consist in punching the twyers by this mechanism so often that it will be impossible for chilled accretions to form in any twyer of the series. If this be not done and if chilled accretions be permitted to obstruct any one or more of them, this neglect may cause trouble 30 and may thereafter obstruct or prevent the successful working of the apparatus. In short, the twyers cannot well be punched too often; but they may easily be punched too seldom.

We prefer to use converters or furnaces whose walls 35 are composed of heavy metal blocks, such for instance as blocks made of copper, steel or iron. These may be supplemented with an interior lining of basic refractory, such for instance as magnesite, chrome &c.; or they may be supplemented with an acid lining such 40 for instance as silica brick or silica compacted into position in a plastic condition. The converter may be composed of exterior water-jackets or air-jackets, supplemented with basic or acid interior linings. In any event we prefer to line each twyer with a seamless 45 brass tube of the proper size.—1st.—Because it will absorb the wear inseparably incident to the punching process and because it may be quickly and cheaply replaced. 2nd.—It effectually prevents the twyer rods from breaking down or injuring any interior lining. 50 3rd.—It offers less resistance or friction to the entering blast and to the rod.

The walls of any of our converters will remain constant in thickness, because we do not depend upon the corrosion of the silica lining to satisfy the iron in our 55 matte. This fact we find of great importance in connection with our invention, because it enables us to regulate the travel of each punching-bar at will and to an exact nicety, so that it will effectually perform its mission.

60 Referring now to the drawings: Our first form of mechanism as shown is arranged to punch the twyers in series of four at one time and at intervals of one minute, and with the end of each punching-rod obstructing the entrance of the blast in each orifice for a 65 period that does not exceed five seconds. Its speed

may be increased or reduced so as to produce the best results.

6 in Fig. 1 represents a three horse-power electric motor, although any other size may be used and any other form of power may be utilized, if preferred. The 70 motor shown in the drawings is mounted, for convenience and economy, on one end of the wind box. Its speed is preferably 1200 revolutions per minute. It communicates its power through the pinion 7 to the spur-wheel 8. This, in turn, through its shaft, actuates the pinion 9, which latter actuates the spur-wheel 10 and it, through the medium of its shaft, actuates the pinion 11 which in turn propels the spur-wheel 12. The latter is securely fastened to the main shaft 13, which extends the length of the converter and carries 75 the wheels 14. Each of these wheels 14 is provided with gearing throughout a sufficient portion of its periphery to actuate periodically and intermittently the pinions 15. Only the requisite number of teeth are provided on each wheel 14 to propel its companion 80 pinion 15 one complete revolution. In the drawings the wheels 14 are speeded to make one revolution per minute; hence each pinion 15 makes one complete revolution in a fraction of a minute and during the remainder of the time it remains dormant. The wheels 90

14 are so arranged upon the main shaft that only one pinion 15 will be actuated at a time; hence the entire apparatus can thus be operated with a minimum consumption of power. When the pinion 15 is actuated by the spur-wheel 14, it communicates power through 95 its shaft to the lever 16. The lever 16 actuates the reciprocating lever mechanism 17. In Fig. 2, 17 is illustrated in two different positions. In one the punching-bar is shown at its greatest thrust into the converter, and it is also shown in its position of rest, 100 after the punching-bar has been driven into the converter and has been again pulled out of the converter wall, in which position it remains dormant until the cog-gearing on the wheel 14 again actuates it after an interval of about one minute, in performing its mission 105 of punching the twyer-orifice.

In Fig. 2 we illustrate at 18 a convenient device for applying power to the punching-bar 19, through the lever 17. The punching-bar 19 is shown equipped with a sleeve, gib and set-screw, which are more fully 110 illustrated in detail in Fig. 4. This sleeve may by means of a hand-wrench be quickly tightened in any position on the punching-bar that is desired. Thus, if the end of the punching-bar from time to time, burns off, through long, continuous service, this sleeve may 115 be quickly loosened and moved to a new location so that the bar will enter the twyer the requisite distance to produce effective work. In Fig. 3, the working of this apparatus is illustrated more in detail and in addition, the lever 17 is shown in a new position, in which 120 it can be quickly placed if desired, in order that the punching-bar 19 may be temporarily actuated by hand. A single twyer might be temporarily obstructed, through the burning off of the interior end of the punching-rod. In such an event it may be thrown out of 125 service temporarily and the punching-rod operated by hand. The sleeve 20 may then be used to hold the dog, and the punching-rod may be removed from the twyer by means of the dog or with a sledge hammer, if preferred. In lieu of using the sleeve for the pur- 130

pose stated, we also show in Fig. 5, a punching-rod that is provided with a head for the purpose of securing the dog, when it is desired to extract or to drive the punching-rod into the twyer-orifice by hand. 5 Fig. 5 also illustrates a convenient method of adjusting the location of the lever 17 on the punching-rod 19, by means of the screw hand-wheels 21. This is an alternate device, supplementary to that shown in Fig. 4 and in the other illustrations of the series wherein the 10 sleeve provided with a gib and set-screw is used.

In addition to the regular ball-valve 22 in the windbox, as illustrated in Fig. 3, we may provide the converter with a stuffing-box as shown at 23.

24 illustrates the seamless brass tube hereinbefore 15 described with which we prefer to line the twyer-orifice. In Fig. 3 this orifice is shown with a contracted tip near the interior portion of the vessel-wall. When the punching-rod is at rest, its tip will be back in the larger portion of the orifice, so that the blast passes 20 freely around it and through the contracted portion into the molten bath. During the short time that the punching-bar is thrust forward by the mechanism, it temporarily enters the contracted portion of the orifice, as shown at 25. The contracted portion of the orifice 25 is considerably larger than the tip of the punching-rod, so that the blast can at all times pass freely around it and can exert its full pressure during the act of withdrawing the punching-rod from the interior of the vessel. This prevents the molten bath from following the punching-rod and filling the orifice where 30 it would quickly chill within the walls of the converter if this provision were not made.

It will here be explained that when the punching bar is in its retracted position, it lies in the channel of 35 the cold entering air blast, whereby its forward end is clean and cold prior to the act of punching. The power mechanism which actuates the punching bar is arranged to work the bar so as to make a sudden forward stab through the twyer into the converter and is 40 then instantly jerked out of the orifice and brought back into the rear portion of the twyer, whereby it is absolutely impossible in this short time to have the temperature of the bar materially raised, and in any event, it is not sufficiently increased to make it possible 45 for molten matte or slag to adhere thereto.

In any form of twyer punching, whether the work is done by machinery or by hand, ample provision must be made for the removal of congealed slag or 50 matte scale that will inevitably accumulate on the tip of the punching-bar, each time the same is driven into the molten bath. In all hand-punching serious difficulty constantly occurs and is a constant source of trouble. The punching-bar frequently sticks in the orifice, thus holding the tip of the bar for a time immersed 55 in the hot, corrosive matte. In this position it quickly becomes heated, sometimes to the fusion point. Its exterior surface is then violently attacked by the corrosive elements in the bath, and while thus heated perhaps to the fusion point a bond of matte and 60 slag is formed with the body of the bar that is practically as firm and indestructible as the metal of the bar itself. Such accretions then cause the bar to stick firmly in the orifice and necessitate the ultimate removal of the bar with sledges and dogs. After it 65 has been removed the accretions can only be separated

from it by plunging the tip of the bar in cold water and by hammering it with sledge hammers. We prevent the occurrence of troubles of this description.

Referring again to the drawings, 26 in Figs. 7, 8, 9, and 10 illustrates a removable plug, that may be composed of tool steel, nickel or manganese steel, chilled iron, steel or malleable iron castings, or such similar material; the object being to use some material that will hold cutting edges at 27 where the punching bar passes backwards and forwards obliquely through the 75 orifice in the plug provided for that purpose, and will also withstand successfully the heat of the chilled accretions of slag and matte and the heat of the punching-bar each time the latter is withdrawn from the molten bath. We have found that malleable iron is a 80 very suitable material for this purpose, but many other materials may successfully accomplish the desired result.

When work is commenced in this converter, the punching-bar will be at a state of rest, as far removed 85 from the interior of the vessel as the lever 17 will permit. In this position it will be continuously subject to the cooling influence of the entering blast which will surround it on all sides. It will therefore be thoroughly cooled before it commences its work of 90 punching the tuyers. When the mechanism is started it will make one quick thrust through the interior wall and for a short distance into the molten bath whence it will be immediately withdrawn. The bar will be cold to start with, and its sojourn within the molten 95 bath cannot exceed five seconds, when it is immediately withdrawn. It will therefore be impossible for it to become sufficiently heated during this brief period so that the corrosive matte can seriously heat it or seriously attack its exterior. For these reasons a 100 firm bond of matte or slag cannot form upon its tip as is now so common in hand-punching. In other words the bond between the bar and any chilled accretions that may stick to it will be so slight that the latter can be removed when it is returned through the plug 26 105 to its position of rest. As these chilled accretions are cut loose from the bar, they drop into the receptacle 28 provided for their reception. This receptacle as shown in Figs. 7 and 8 is approximately twelve inches long by about one and one-half inches wide. It may 110 be made greater or less. After the bar has thus been stripped of its accumulation of chilled accretions and after it has been restored to its position of rest, it will thereafter be again surrounded by the cold entering blast for a period of fifty-five seconds, during which 115 time it will be afforded an opportunity, under favorable surrounding conditions, to be cooled thoroughly, before it is called on to make another thrust into the molten bath.

Figs. 7 and 8 illustrate at 29 the provision made for 120 the ready entrance of the punching-rod through the rear of the plug 26. 27 illustrates the cutting edges on the plug 26 for the removal of scale as herein described. 30 at each end of the plug 26 illustrate the circular sections which are intended to steady it and to hold 125 it securely in position within the converter wall. 31 illustrates a gasket, which may be made of asbestos or of other suitable material and is intended to make an air-tight seal for the plug 26 in order to prevent the escape of the air-blast at this point. We do not con- 130

sider this feature necessary. If the circle of the plug at 30 be made a snug fit, the escape of blast will be so trifling as to be unimportant.

Fig. 8 illustrates the plug 26. It shows the orifice 5 through which the punching bar passes, with its flaring sides towards the rear, in order to facilitate the entrance of the rod. It also illustrates at 32 the cutaway portion of the plug 26 in order at this point to permit the free passage of the blast past it on each side, through the 10 twyer-orifice.

Fig. 9 illustrates a side view of the plug 26. It shows the grooves 32 through which the air-blast passes around the plug 26 into the converter.

Fig. 10 illustrates a convenient method of quickly 15 securing the plug 26 into its position in the converter wall so that it will be firmly held while performing its work. By a simple turning of the hand-wheels 33, which are mounted on hinges as shown in Fig. 7, the plug 26 may be instantly released and removed or it 20 may be withdrawn a few inches and held in this position, whereupon the escaping blast through the receptacle 28 will instantly discharge any accumulation of scale.

Another mechanism with which our invention may 25 be successfully practiced, consists of a framework or car, Figs. 11, 12, 13, 14 and 15, which constitutes a carrier for long cylinders. The framework may either be hung from the ceiling, it may be swung from an overhead trolley car, or it may be mounted on a car 30 that travels on the ground level. It may be provided with one, two or with any number of cylinders, the pistons of which have sufficient travel to admit of the direct punching of the twyers. It will be found convenient to make provision for attaching this framework 35 temporarily to the converter on either side as a means of absorbing the thrust of the piston or pistons. The power utilized for this purpose may be compressed air, steam or hydraulic pressure. In the drawings we show the pistons actuated by compressed air intermittently 40 and the valves to the cylinders actuated by an electric motor.

Fig. 14 illustrates the framework or carriage of the apparatus.

Fig. 15 in Figs. 11, 12 and 13, illustrates the wheels that 45 carry the framework.

Fig. 16 in Fig. 13 illustrates the track or tramway, on which the wheels that carry the carriage or framework travel. This track may be on the ground level or overhead, as preferred.

Fig. 17 in Figs. 11, 12 and 13 illustrates cylinders whose piston-rods 38 actuate the punching-bars 39 by means of the cross head 40.

Fig. 12 of the drawing shows four punching-rods attached to and operated by one cross-head which is 55 actuated by a single cylinder. Any number of punching-bars may however be operated by a single cross-head, without departing from the spirit of our invention.

Fig. 18 in Figs. 11 and 12 illustrates bell-mouthed guides 60 for the punching-bars, that are intended to catch the tip of the punching-rod after each removal from the orifice and to facilitate its passage through the windbox and twyer in performing its mission.

Fig. 19 in Figs. 11, 12 and 14 illustrates the electric motor 65 which communicates power to the shaft 43 by means

of the gear-wheels 44. Power is communicated from the shaft 43 by means of the endless chain 45, Fig. 12, to the shaft 46. The latter communicates power by means of an eccentric 47, Figs. 11 and 12, to the operating-valve 48 by means of the eccentric rod 49. In 70 this manner the operating-valve 48 is operated periodically or intermittently at any desired speed, by a proper adjustment of the electric motor so that it will accomplish the result desired. It is only intended that the eccentric rod 49 shall operate the valve-operating 75 mechanism 48 to admit power at stated intervals to one side of the cylinder as shown at 50, whereby a piston-rod 38 carrying the cross-head 40 and the four punching-bars 39 is driven forward. After the piston-rod has accomplished its full travel, the cross-head 40 engages 80 the collar 51 which operates the rod 52 which in turn actuates the valve in opposite direction as shown at 53.

Figs. 14 and 15 are intended to illustrate in detail, one mode of removing congealed scale from the punching-rod, each time the same is withdrawn from the 85 orifice, should any such scale exist.

Attention is again called to the fact that because the bar is thoroughly cooled before it is driven forward to punch the orifice, because its sojourn within the heat area of the interior is short and because it is constantly 90 subjected to the chilling effect of the entering blast under pressure which surrounds the tip at all times, it will be impossible for molten slag or matte to form a bond with its surface. Nevertheless, in order to make assurance doubly sure and to guarantee the clean condition of the rod before it enters the orifice, we preferably provide a water-cooling jet 54 with its catch-basin 55 so-located that it can play a stream of cold water to any desired extent and in any desired volume over the surface of the punching-bar during its withdrawal from 100 the orifice. The shrinkage of molten slag or matte in cooling is so great that it will so contract any hot accretions as to cause them to crack and drop from the rod. If preferred, the equivalent of this chilling device in the form of a mop or brush thoroughly saturated with 105 moisture may be used, without departing from the spirit of our invention. In addition to this device we provide preferably, rollers 56, Figs. 14 and 15, whose faces are grooved as shown in Fig. 15, to correspond closely with the exact diameter of the punching-rod. 110 These rollers revolve and thoroughly crush and remove any chilled accretion during the withdrawal of the punching-bar 39, especially after it has been thoroughly chilled and thus rendered brittle by the action of the water-jet. The faces of these rollers may be corrugated, 115 if preferred.

In addition to the rollers herein described, we also preferably provide a thimble 57, Fig. 14, that has cutting edges on the side nearest to the converter. The size of this thimble with its cutting edges is such that 120 it neatly fits the entire circumference of the punching-bar 39 and during the withdrawal of the punching-bar the cutting edges scrape loose and remove thoroughly and effectually every vestige of scale that may have succeeded in passing the two devices hereinbefore described.

In Fig. 14, one form of punching-bar is shown that is uniform in diameter throughout its entire length, as a means of facilitating the successful operation of the three scale-removing devices as described. The 130

- twyer-orifice at 58 is larger than the diameter of the punching-bar, so that blast under pressure may pass freely around the bar at all times and especially during its withdrawal from the interior wall of the converter.
- 5 Were the diameter of the punching-bar made practically the same as the diameter of the orifice at 58, it will be apparent that when this bar is withdrawn from the interior wall of the converter the molten matte would follow it out into the twyer-orifice where it 10 would chill and thus effectually clog the twyer. In order to prevent this result, the tip of the punching-rod is made materially less in diameter than the diameter of even the contracted portion of the twyer-orifice. For this reason the blast under pressure can 15 constantly pass around the outside diameter of the bar during the latter's withdrawal, and indeed at all times. This pressure has the effect at all times of preventing the escape of any molten material through the twyer-orifice.
- 20 In Fig. 11 the punching-rod is shown with two different diameters. The smaller diameter is shown at 39 and the larger diameter is shown at 59. The reason for this is because in Fig. 11 no apparatus is shown for the removal of congealed accretions, for the reasons hereinbefore given. In regular practice, no such accretions will accumulate upon the rod beyond possibly some slight grit. A stuffing-box is shown at 60 which it is intended shall contain packing of some description as a means of preventing leakage of air from 25 the wind-box while the bar is within the opening. When the bar is out, the ball-valve 61 falls into its seat by gravity and closes the opening thus also preventing the escape of air. The enlarged portion of the punching-bar 59 does not come into contact with any molten 30 material; hence its surface will always be clean, and as a consequence it may safely be permitted to travel through the packing of any description that is used at 60 without fear of any injurious cutting action. The reduced or smaller diameter of the punching-bar as 35 shown at 39 will come into direct contact at its tip at each thrust, with the molten material contained in the converter. Hence when this passes through the stuffing-box at 60 during its withdrawal from the orifice, its diameter is so much less than the diameter of the 40 stuffing-box at 60 that it cannot injuriously cut the packing of any description that may be used.
- Doubtless many modifications and alterations in the means employed for punching the twyers naturally suggest themselves to those skilled in the art, without 45 departing from the spirit of our invention, since we believe we are the first to employ mechanical devices for punching the twyers, instead of punching them by hand.
- We claim:—
- 55 1. A smelter having a series of twyers, slag-removing means therefor operating independently of each other, and an actuator common to all of said means, substantially as described.
2. A smelter having a series of twyer orifices, slag-removing means for the orifices, and an actuator common to the slag-removing means for successively operating the same, substantially as described.
3. A smelter having a series of twyers, punches for the 50 twyers operating independently of each other, and actuating means common to all the punches, substantially as described.

4. A smelter having a series of twyer orifices, punches for the twyers, and actuating means common to all the punches for successively actuating them, substantially as described.

5. Means for increasing the air-blast of converters and furnaces, which consists in the combination with such converter or furnace having twyer-orifices, of punching-bars extending thereto, and automatic means for operating said punching-bars periodically; substantially as described.

6. A smelter having twyer orifices, punching bars working in the orifices and connected in groups, and an actuator common to all the groups for operating them successively and periodically, substantially as described.

7. Means for increasing the air-blast of converters and 80 furnaces, which consists in the combination with such converter or furnace having twyer-orifices, of punching-bars extending thereto, operating mechanism connected with the punching-bars for reciprocating them, and a holding device adapted to permit longitudinal adjustment of 85 the bars to compensate for their burning off; substantially as described.

8. Blast apparatus including a twyer having its orifice contracted in diameter at its inner end, and a punching-bar working in the twyer and having its front end portion of a diameter to work freely through the contracted portion of the twyer orifice, the punching-bar being normally disposed with its forward end in rear of the contracted portion of the orifice to prevent obstructing the twyer, substantially as described.

9. Blast apparatus including a twyer having the inner end of its orifice contracted in diameter, a wind-box, a tube leading from the wind box into the twyer orifice and constituting a lining therefor, and a punching-bar working through the wind box, the tube and the twyer orifice and having its forward end of a diameter less than that of the contracted portion of the twyer, said bar being normally located with its forward end in rear of the contracted portion of the twyer to prevent choking thereof, substantially as described.

10. Means for increasing the air-blast of converters and furnaces, which consists in the combination with such converter or furnace having twyer-orifices, of punching-bars extending thereto, and means for removing scale from the bars; substantially as described.

11. Means for increasing the air-blast of converters and furnaces, which consists in the combination with such converter or furnace having twyer-orifices, of punching-bars extending thereto, operating mechanism connected to the twyer-orifices with the punching-bars for reciprocating them, and means for removing scale from the bars; substantially as described.

12. Means for increasing the air-blast of converters and furnaces, which consists in the combination with such converter or furnace having twyer-orifices, of punching-bars extending thereto, means for removing scale from the bars, and a receptacle at the twyer-orifices to receive the detached scale; substantially as described.

13. Means for increasing the air-blast of converters and furnaces, which consists in the combination with such converter or furnace having twyer-orifices, of punching-bars extending thereto, and cutting or scraping devices to remove scale from the bars; substantially as described.

14. Means for increasing the air-blast of converters and furnaces, which consists in the combination with such converter or furnace having twyer-orifices, of punching-bars extending thereto, and plugs having cutting edges to remove scale from the bars; substantially as described.

15. Means for increasing the air-blast of converters and furnaces, which consists in the combination with such converter or furnace having twyer-orifices, of punching-bars extending thereto, and plugs extending transversely across the twyer-orifices having cutting edges to remove scale from the bars; substantially as described.

16. Means for increasing the air blast of converters and furnaces, which consists in the combination with such converter or furnace having twyer orifices, of punching-bars extending thereto; scale-removing devices for the bars and means for cooling, contracting and removing such scale by an application of a cooling medium; substantially as described.

17. Blast apparatus having automatic means to prevent clogging of the twyer orifices by chilled slag or matte, substantially as described.

18. Blast apparatus having a series of independent 5 twyer-punching bars, and power-actuated means common to the bars for successively operating the same, substantially as described.

19. Blast apparatus having a series of independent 10 twyer-punching bars, and power-actuated means common to the bars for successively and periodically operating them, substantially as described.

20. Blast apparatus having a series of independent twyer-punching bars, and means common to all of the bars for successively operating them, each bar being as-

sociated with the operating means by a detachable connection which is accessible for disconnecting any bar independently of the other bars, substantially as described.

21. Blast apparatus having a series of independent twyer-punching bars, a continuously operating motor, and means controlled by the motor for periodically and successively actuating the bars, substantially as described.

In testimony whereof, we have hereunto set our hands.
